Specification for Design.

Patented June 13, 1916.

Application filed March 9, 1916. Serial No. 83,205. Term of patent $3\frac{1}{2}$ years.

To all whom it may concern:

Be it known that I, JOHN KORZINEK, a citizen of the United States, residing in the city of Passaic, county of Passaic, State of New Jersey, have invented a new, original, and ornamental Design for a Floral Border for Wall-Paper, of which the following is a specification, reference being had to the accompanying drawing, forming a part thereof.

The figure of the drawing is a plan view of a portion of a wall paper border illustrating my new design.

The design comprises a bunch of apple blossoms and buds A with a narrower border behind it made up of sprigs of blossoms B and intervening bands of ribbon C.

Above the bunch A is a flat straight band D on which are interspersed individual blossoms. Depending from each side of the bunch A are strings of blossoms E, to form loops connecting the bunches.

The design as shown is intended to be repeated or matched out upon either side indefinitely as is usual in such cases.

What I claim is:

The ornamental design for a floral border for wall paper as shown and described.

JOHN KORZINEK.
